UNITED STATES PATENT OFFICE.

HARRY H. BERRYMAN, OF CHICAGO, ILLINOIS.

WINDOW STOP AND ANTIRATTLER.

Application filed January 8, 1923. Serial No. 611,519.

To all whom it may concern:

Be it known that I, HARRY H. BERRYMAN, a citizen of the United States, residing at Chicago, in the county of Cook and State 5 of Illinois, have invented new and useful Improvements in Window Stops and Anti-rattlers, of which the following is a specification.

My invention relates to window stops and 10 anti-rattlers, and more particularly to the provision of a device of this character which is especially adaptable for holding the windows of automobiles of the closed or limousine type in a predetermined elevated position 15 or to prevent rattling thereof, although not necessarily restricted to this use.

An important object of the invention is the provision of a window stop of the kind stated which is neat and attractive in appearance, positive in operation and which 20 may be cheaply manufactured.

A further object of the invention is to furnish an article of the character set forth which embodies a novel and improved means 25 for moving the window engaging element to and from operative position.

With the above and other objects in view as will become more apparent as the description proceeds, the invention comprises 30 a novel construction and arrangement of parts to be hereinafter described and claimed, and in order that the same may be better understood, reference is had to the accompanying drawing forming a part of 35 this specification.

Figure 1 is a plan view of a window stop embodying my invention;

Fig. 2 is a central vertical section through the same, and

Fig. 3 is a view similar to Fig. 1 illustrating the device in operative position.

Referring specifically to the drawing, wherein like reference characters designate similar parts throughout the several views, 45 numeral 5 denotes a base plate having apertures 6 therein for the reception of screws or other suitable fasteners for securing the device upon a window sash or frame. This plate 5 is formed with two pairs of opposed 50 upwardly directed portions 7 for sliding engagement with the longitudinal edges of a sheet metal slide, which latter is provided with a short longitudinal slot 9 intermediate its ends to receive a stud 10 rising from the medial portion of the plate 5. The function 55 of this slot 9 is to limit the sliding move-

ment of the slide 8. The forward end of the slide 8 is bent upwardly toward the base plate 5 as shown at 8^a and its end 8^b is bent forwardly to form the top of a socket 60 for the reception of a soft rubber stop 11, the side walls of this socket being formed by forwardly directed wings 8^c carried by the portion 8^a. The rear portion of the slide 8 is also upwardly directed as shown 65 at 8^d for a purpose to be presently described. It will be understood that the slide 8 may be stamped from a blank of sheet metal and the stop holding socket just described formed in an obvious manner. The 70 means for moving the slide 8 to and from engagement with the window comprises an eccentrically pivoted cam 12 receiving the stud 10 and resting between the upwardly directed portions 8^a and 8^c of the slide 8. 75 The free end of the stud 10 is threaded for the reception of a nut 13 and spring washers 14 may be provided above and below the cam 12 to prevent any looseness thereof.

From the foregoing description read in 80 connection with the accompanying drawing, it will be readily apparent that when the device has been secured upon the window sill 15 of a motor vehicle as illustrated in Fig. 3, the stop 11 in the socketed end of 85 the slide 8 will be moved to and from engagement with the window pane 16 upon rotation of the cam 12 through the medium of the handle 12^a. In advancing the slide 90 with its stop 11 toward the window pane the cam 12 works against the upwardly directed portion 8^a of the slide and when retracting it therefrom it cooperates with the upwardly directed portion 8^c at the rear of 95 the slide. The handle 21^a of the cam is formed of relatively thin material and is twisted as shown at 12^b to form a finger grip and to clear the up-turned end 8^c of the slide.

The spring washers 14 serve to hold the 100 stop 11 in a predetermined position and prevent movement of the cam 12 except when desired. It will be clear that when the stop 11 has been moved to the position shown in Fig. 3, that the window pane may be held in a predetermined position and any rattling thereof will be prevented.

In summarizing, it will be seen that the 110 offset 8^a not only constitutes one wall of the socket for the reception of the window contact element 11, but also forms an abutment for the cam 12.

Attention is also directed to the fact that the lower spring washer 14 not only holds the cam 12 against accidental turning but also positively prevents rattling of the bolt or plate 8.

In accordance with the patent statutes I have illustrated my invention in concrete form and have described it as functioning in a specific manner, but it will be understood that I do not propose to limit myself strictly to the precise embodiment disclosed, since various modifications and changes will immediately suggest themselves to those skilled in the art without departing from the spirit of the invention, the scope of which is set forth in the appended claims.

Having thus described my invention, what I claim as new and desire to secure by Letters Patent is:

- 20 1. A window stop and anti-rattler comprising a longitudinally slidable bolt having an offset provided on opposite edges thereof with wings, said offset and the wings thereof, and the adjacent terminal portion 25 of said bolt constituting the walls of a socket, a window contact element received in said socket, the rear end portion of said bolt being extended upwardly to form an abutment, a cam located between said offset and said abutment and having means whereby the same may be turned, a pivot element 30 supporting said cam, spring washers ar-

ranged on opposite sides of the cam, one of said spring washers being confined between said cam and said bolt, and means carried 35 by said pivot element to hold the cam on the pivot element, said sliding bolt being formed with a longitudinal slot receiving said pivot element, and the end walls of said slot being adapted to engage the pivot 40 element to limit the movement of the sliding bolt.

2. A window stop and anti-rattler comprising a longitudinally slidable bolt having one end portion provided with a laterally projecting portion having a socket and the other end portion provided with an abutment, a window contact element received in said socket, a base plate supporting said bolt, a pivot element carried by 50 said base plate and extending through said bolt, a cam mounted on said pivot element and confined between said end portions of the bolt and having operating means, and spring washers mounted on said pivot element on opposite sides of said cam to hold the cam against accidental turning, one of said spring washers being confined between the cam and the bolt and holding the bolt 55 against rattling.

In testimony whereof I affix my signature.

HARRY H. BERRYMAN.
